US00D852755S

(12) **United States Design Patent** (10) Patent No.: **US D852,755 S**
(45) Date of Patent: **** Jul. 2, 2019**

(54) **CONNECTOR CONTACT**

- (71) Applicant: **Cheng Uei Precision Industry Co., Ltd.**, New Taipei (TW)
- (72) Inventors: **Han-Wei Wang**, New Taipei (TW); **Sheng-Yuan Huang**, New Taipei (TW); **Pei-Yi Lin**, New Taipei (TW); **Te-Hung Yin**, New Taipei (TW)
- (73) Assignee: **CHENG UEI PRECISION INDUSTRY CO., LTD.**, New Taipei (TW)

(**) Term: **15 Years**

(21) Appl. No.: **29/643,143**

(22) Filed: **Apr. 4, 2018**

(51) LOC (11) Cl. **13-03**

(52) U.S. Cl.

USPC **D13/154**

(57) **CLAIM**

The ornamental design for a connector contact, as shown and described.

DESCRIPTION

FIG. 1 is a perspective view of a connector contact showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets

FIG. 1

FIG. 2

FIG. 3

FIG. 4

FIG. 5

FIG. 6

FIG. 7
